UNITED STATES PATENT OFFICE.

CHARLEY DAY, OF CLEVELAND, OHIO.

ADJUSTABLE WINDOW-SHADE BRACKET.

Application filed May 23, 1919. Serial No. 299,265.

To all whom it may concern:

Be it known that I, CHARLEY DAY, a citizen of the United States, residing at 1036 Hamilton Ave., in the city of Cleveland, 5 county of Cuyahoga and State of Ohio, have invented a new and useful Improvement in Adjustable Window-Shade Brackets, of which the following is a specification; the principle of the invention being herein explained, and the best mode in which I have 10 contemplated applying that principle so as to distinguish it from other inventions.

My invention relates to adjustable window shade brackets in association with supports 15 provided each with an offset to which the brackets are to be directly attached.

The object of my invention besides providing brackets which are adjustable toward and away from each other so as to be suitable for various breadths of window shades, 20 is to space the plane of movement of the brackets a suitable distance from the window sash to prevent obstruction of their adjusting movement by any protuberance on 25 the window sash. While window shades are generally cut to various standard sizes, slight variations in their intended length occur or in time manifest themselves due to warpage or other distortional causes.

30 Adverting to the drawings:—

Fig. I is an elevation of a window showing shade mounted in my improved brackets.

Fig. II is a horizontal section taken on 35 line II—II in Fig. I looking in the direction indicated by the arrows.

Fig. III and Fig. IV are an enlarged plan and an elevation respectively of one of my improved brackets.

40 Fig. V and Fig. VI are enlarged sectional views taken on line V—V and VI—VI respectively of Fig. I.

A window 1 is framed on opposite sides by jamb portions having flat areas 2 and 3 45 respectively and a little further removed from the edge of the window not uncommonly fashioned with protuberances, offsets or beads 4 and 5 respectively. Ordinarily, window shade brackets are permanently secured to the flat areas 2 and 3 a predetermined distance apart depending upon the width of the window and of course also upon the width of the shades to be drawn down in front of the same. The range of adjustment movement crosswise of the flat 50 areas 2 and 3 besides being limited within

the confines of the beads 4 and 5 would eventually, after repeated adjustments, disfigure the window sash.

Accordingly, in addition to the brackets proper, I provide a pair of supports 6 and 7 intended to be permanently secured to the flat areas 2 and 3 as by screws 8 and 9. Intermediately of the screws the supports 6 and 7 are formed with raised portions or offsets 10 and 11 respectively and the height of such offsets should somewhat exceed the extent of projection of the beads 4 and 5. It is to the offsets 10 and 11 that I propose to adjustably attach a pair of brackets 12 and 13 60 so that if required their movement parallel to the plane of the window will be out sufficiently far to clear the beads 4 and 5. The remote ends 14 and 15 of the brackets 12 and 13 with reference to each other, are bent 70 outwardly substantially at right angles to the window sash. As usual, the end 14 of one bracket is provided with a round hole 16 while the end of the other bracket is fashioned with a slot 17 open at its upper 75 end. The portions of the brackets 12 and 13 which abut the offsets 10 and 11 are fashioned each with an elongated slot designated by the numerals 18 and 19 respectively, through which slots machine screws 80 20 and 21 extend to continue through holes 22 and 23 in the supports whereby to engage nuts 24 and 25 which are held against turning in square countersunks 26 and 27 in the offsets 10 and 11. If the support is of wood, 90 nails 28 and 29 may be used to hold the nuts in the recesses, whereas if the parts are metal stampings other means for such purpose could be readily contrived. Studs 30 and 31 which are also secured in the offsets likewise 95 project through the slots 18, 19 and act to limit the adjustment to a straight line movement. As will be readily understood a loosening of the screws 20 and 21 enables the brackets to be slid therealong and thereafter fixed the desired distance apart by retightening of the screws.

I claim:—

1. A device of the character described comprising a support having an offset exceeding in projection any window frame protuberance and provided with a hole extending in the direction of projection of said offset, said support being fashioned on the side opposite to the side from which the offset projects with an angular countersunk around the inner end of said hole, a bracket 105 110

provided with a slot extending at right angles to the direction of said hole, a nut in said countersunk, means for holding said nut in place in said countersunk, a machine screw passed through said slot, occupying said hole and having its head engaging said bracket at two defining edges of said slot, said screw furthermore having its thread engaging said nut, and a stud carried by said offset, said stud being disposed to one side of said screw and also projecting through said slot whereby the stud and screw together prescribe the direction of adjustment movement in a plane outwardly beyond any window frame protuberance.

2. A device of the character described

comprising a wooden support provided on one side with an offset and on the other side opposite said offset with an angular countersunk, said support being furthermore provided with a hole extending through said offset and communicating with said countersunk, a bracket provided with a slot, a nut in said countersunk, a screw occupying said hole and having its threads engaging said nut and nails driven in said wooden support around said nut to hold said nut in place in said countersunk whereby to facilitate tightening of said screw.

Signed by me, this 21st day of May, 1919

CHARLEY DAY.
